UNITED STATES PATENT OFFICE

161,023

CHRISTMAS TREE DECORATIVE ORNAMENT

Kurt W. Herman, Richmond Hill, N. Y.

Application October 25, 1948, Serial No. 149,272

Term of patent 14 years

(Cl. D29—1)

To all whom it may concern:

Be it known that I, Kurt W. Herman, a citizen of the United States, residing at Richmond Hill, L. I., N. Y., in the county of Queens and State of New York, have invented a new, original, and ornamental Design for a Christmas Tree Decorative Ornament, of which the following is a specification, reference being had to the accompanying drawings, forming part thereof, in which—

Figure 1 is a front view of a Christmas tree decorative ornament showing my new design;

Fig. 2 is a top view;

Fig. 3 is a back view thereof; and

Fig. 4 is a side edge elevational view thereof.

I claim:

The ornamental design for a Christmas tree decorative ornament, as shown.

KURT W. HERMAN.
